BAG EMBODYING ONE OR MORE TIE-STRIP PORTIONS, AND SHEET MATERIAL PROVIDING THE SAME

Roman E. Shvetz, 580 5th Ave., New York, N.Y.
Filed Nov. 26, 1963, Ser. No. 326,277
7 Claims. (Cl. 229—62)

This invention relates to bags of sheet material having an open top and more especially to picnic and sandwich bags and bags of like nature. The closing of the top after articles or material have been put into such a bag is often a matter of considerable difficulty, particularly if the bag is formed from plastic, and this is especially so when suitable tying material is not immediately available.

With the following and other considerations in view the present invention contemplates the provision of bags having tie-strip portions which are part of the sheet material of which the bag is formed and which are set off from the remainder of the sheet material in a particularly effective and desirable manner which permits the transformation of a tie-strip portion into a tie strip after the contents of the bag have been put into the bag. In certain of its more specific aspects, the invention further contemplates the provision of bag-forming material, such, for example, as flattened tubular material, from which such a bag or, preferably, a plurality of such bags may be formed.

The invention accordingly comprises articles possessing the features, properties, and the relation of elements which will be exemplified in the articles hereinafter described and the scope of the application of which will be indicated in the claims.

For a fuller understanding of the nature and objects of the invention, reference should be had to the following detailed description taken in connection with the accompanying drawings, in which:

FIGURE 1 is an elevation of one form of bag embodying the invention;

FIG. 2 is a perspective view with the top spread somewhat;

FIG. 3 is a similar view showing the tie strip portions after the separating action by which they become tie strips;

FIG. 4 is a similar view showing one type of tying up a bag by the tie strips of FIG. 3;

FIG. 5 is a view similar to FIG. 2 showing a modification;

FIG. 6 is a similar view showing a modification wherein a tie strip portion merges at both ends with the sheet material of which it and the bag are composed;

FIG. 7 is a similar view showing the tie strip portion of FIG. 6 separated to provide a single tie strip;

FIG. 8 is a similar view showing the separated tie strip of FIG. 7 torn centrally to provide two tie strips;

FIG. 9 is a similar view showing the inseparable top piece turned down;

FIG. 10 is a similar view showing the tie strips of FIGS. 8 and 9 tied;

FIG. 11 is a similar view showing a further modification;

FIG. 12 is an elevation showing a piece of flattened tubular sheet material adapted to be separated transversely to provide a plurality of bags such as shown in FIG. 11;

FIG. 13 is a perspective view of the bag of FIGS. 6 and 7 with the tie strip of FIG. 7 arranged for fastening the bag closed in another manner; and

FIG. 14 is a similar view showing the bag of FIG. 13 fastened in that manner.

In accordance with the invention, the tie strip portion or portions are part of the sheet material of the bag itself. It or they will have one end unitary and continuous with and merging into the sheet material at the open end 5 of the bag and may have as one longitudinal edge a part of the open edge of the bag and have the other longitudinal edge defined by a score line or other separation line of less extent than the tubular extent of the bag. The other end may also be defined by a score line, or may 10 be defined by a slit or notch or other cut-out portion, or, in instances where a single tie-strip portion is to be formed into two tie strips, as by tearing, after separation of the portion from the bag, or where a bow-shaped or more nearly circular tie strip is to be used as a fastener in 15 such form or in a specially-tied form, may merge into the sheet material of which it is a part so as to be permanently secured thereto at both ends.

In the particular exemplification illustrated in FIGS. 1-4 there is shown a plastic bag 5 of the type commonly 20 used as sandwich or picnic bags and formed of plastic, such, for example, as transparent polyethylene. The bag is composed, in any event, of sheet material, and in the present instance of a flattened tubular single sheet which is closed at or near its bottom edge by a seal line 6 which 25 may be a heat seal. The bag thus comprises a front side 8 and a rear side 9, a top edge 10 which is continuous about the open top, and edges 11 and 12 extending between the top edge 10 and the seal line 6. At the top of the side 8 is an inseparable portion 15 and a tie-strip portion 16 defined by a score line 17 parallel with a part of the edge 10 and a score line 18 extending between the edge 10 and the score line 17. Here and elsewhere in the showings, the score lines are indicated by a series of short spaced cuts. At the top of the side 9 there is an 30 inseparable portion 20 and a tie-strip portion 21 defined by a score line 22 parallel with a part of the edge 10 and by a score line 23 extending between the edge 10 and the score line 22.

In use, commonly after the contents have been put into 40 the bag, the tie-strip portions 16 and 21 are pulled loose along the score lines 18-17 and 23-22, respectively, and the resulting tie strips shown at 16 and 21 in FIG. 3 are tied. They may be tied as shown in FIG. 4 or otherwise to provide a loose seal, or the portions 15 and 20 may 45 be first turned down on the outside of the edges 11 and 12, respectively, and a tighter seal provided as will be more fully understood by reference to FIG. 10.

In FIG. 5 there is shown a bag 24 which is the same as that of FIG. 1 (and indicated by similar reference numerals) except that the score lines 18 and 23 are replaced by slits 18a and 23a.

In FIGS. 6-10 there is shown a generally similar bag 25 having a single inseparable portion 26 and a single tie-strip portion 27 which merges with and is united to the portion 26 at both ends and is centrally divisible into two tie strips or utilized (by being looped thru itself, for example) to tie up the bag without being divided. The tie-strip portion 27 is defined by a score line 28 which is parallel to the edge 10, and is thereby separable to 55 provide a tie strip as shown in FIG. 7. Thereupon it may, if desired, be torn in two as shown in FIG. 8, or otherwise divided near the middle, to provide two tie strips 30 and 31. Whether or not the tie strip 27 is divided, the inseparable portion 26 may be turned down as shown in FIG. 5, and the top of the bag being bunched and tied, or the tie strip or strips otherwise utilized to fasten a filled bag into a package. The particular tie exemplified in FIG. 10 is effectuated by tie strips 30 and 31.

70 In FIG. 11 there is provided a generally similar bag 35 having an inseparable portion and two tie strips merg-

ing unitarily therewith at their left-hand ends and extending to the right. One of these, shown at 36, is a part of the side 8 and is defined by part of the edge 10, by a separation line in the form of a score line 37 parallel to the edge 10, and by a separation line 38 extending between the edge 10 and the score line 37 and defining one side of a cut-out 39 which is notched out of the top of the bag. The other of these, shown at 41, is a part of the side 9 and is defined by part of the edge 10, by a separation line in the form of a score line 42, and by a separation line 43 extending between the edge 10 and the score line 42 and defining the opposite side of the cut-out 39.

Plastic bags of the nature under discussion are often sold in the form of continuous, flattened tubular strips from which individual bags are separable by the user one at a time. The invention is well adapted for use in such an arrangement, particularly so when the separation lines for the individual bags are made more readily separable than the parallel score lines of the tie-strip portions. In FIG. 12 there is shown a strip 50 of bags 35 defined by seal lines 6 and heavy—easily rupturable—score lines 51 which go thru both sides of the tube. The tie-strip portions of the bags are defined by lighter—less easily rupturable—score lines 52 which go thru both sides of the bags to provide the separation lines 37 and 42, and the flattened tubular strip 50 is cut away at points extending between the lines 51 and 52 at its right hand edge to provide cut-outs 39.

Various of the tie strips shown may, of course, be utilized in other ways than those illustrated. For example, the tie-strips 27 of FIG. 7 may be utilized to fasten the filled bag by first twisting the center portion of the tie-strip so as to cross, in the manner shown in FIG. 13, the secured end portions thereof, and then slipping the tie strip under the bag to hold the bag closed in the manner shown in FIG. 14.

Since certain changes may be made in the above article and different embodiments of the invention could be made without departing from the scope thereof, it is intended that all matter contained in the above description or shown in the accompanying drawings shall be interpreted as illustrative and not in a limiting sense.

I claim:

1. A bag formed of sheet material and comprising a front side and a rear side having generally horizontal top and bottom edges and united at their bottom portions and at two edge portions extending generally upwardly therefrom, a top portion thereof comprising at least one generally horizontal tie-strip portion unitary at at least one end with and merging into said sheet material and extending downwardly from a top edge to a generally horizontal line defining its bottom edge, said sheet material being formed with a rupturable separation line at said horizontal line, and said tie-strip portion being further defined at its other end by a separation-line extending away from said top edge and toward the first mentioned separation line.

2. A bag as in claim 1 wherein the last mentioned separation line is a rupturable line.

3. A bag as in claim 1 wherein the last mentioned separation line is a slit.

4. A bag as in claim 1 wherein the last mentioned separation line defines the edge of a cut-out.

5. A bag formed of sheet material and comprising a front side and a rear side having generally horizontal top and bottom edges and united at their bottom portions and at two edge portions extending generally upwardly therefrom, a top portion thereof comprising at least one generally horizontal tie-strip portion unitary at at least one end with and merging into said sheet material and extending downwardly from a top edge to a generally horizontal line defining its bottom edge, said sheet material being formed with a rupturable separation line at said horizontal line and comprising a plurality of such tie strip portions, one tie strip portion being further defined at its other end by a separation line extending away from its top edge and toward said separation line and another tie strip being further defined at an opposite end by a separation line extending away from its top edge and toward said separation line.

10 6. A bag formed of sheet material and comprising a front side and a rear side having generally horizontal top and bottom edges and united at their bottom portions and at two edge portions extending generally upwardly therefrom, a top portion thereof comprising at least one generally horizontal tie-strip portion unitary at at least one end with and merging into said sheet material and extending downwardly from a top edge to a generally horizontal line defining its bottom edge, said sheet material being formed with a rupturable separation line at said horizontal line, and said sheet material comprising a single-tie-strip portion having two secured ends and a separation line intermediate said ends so that upon the separation of said tie-strip portion at the first mentioned line said tie strip portion will form two tie-strips.

15 7. Tubular sheet material comprising a series of transverse tear lines interspersed with a series of transverse seal lines defining therebetween separate bags having open tops formed by the tearing of the tear lines, the sheet material of each bag comprising at least one tie-strip portion unitary at one end with and merging into said sheet material so as to be secured thereto and of less extent than the edge of the bag at the top and defined in part by a portion of said edge and in part by a rupturable separation line in proximity to said edge and generally parallel to said edge.
